TRAILER HITCH

Lawrence D. Gee, San Diego, Calif.

Application March 7, 1949, Serial No. 1,260

Term of patent 3½ years

(Cl. D14—6)

To all whom it may concern:

Be it known that I, Lawrence D. Gee, a citizen of the United States of America, residing at San Diego in the county of San Diego and State of California, have invented a new, original, and ornamental Design for a Trailer Hitch, of which the following is a specification, reference being had to the accompanying drawing forming a part thereof.

Fig. 1 of the drawing is a perspective view of a trailer hitch showing my new design; and

Fig. 2 is a side elevational view thereof, showing the hitch connection cover in section.

I claim:

The ornamental design for a trailer hitch, substantially as shown.

LAWRENCE D. GEE.
